G. H. HARRIS

HEADER DRIVE MECHANISM

Filed July 9, 1923

Fig. 1

INVENTOR.
George H. Harris
BY *George H. Harris*
ATTORNEY

UNITED STATES PATENT OFFICE.

GEORGE H. HARRIS, OF STOCKTON, CALIFORNIA.

HEADER DRIVE MECHANISM.

Application filed July 9, 1923. Serial No. 650,322.

To all whom it may concern:

Be it known that I, GEORGE H. HARRIS, a citizen of the United States, residing at Stockton, county of San Joaquin, State of California, have invented certain new and useful Improvements in Header Drive Mechanism; and I do declare the following to a full, clear, and exact description of the same, reference being had to the accompanying drawings, and to the characters of reference marked thereon, which form a part of this application.

This invention relates to improvements in the driving mechanism between a thresher and its header by means of which the various parts of the latter are driven, and particularly to the drive mechanisms of side-hill harvesters; my principal objects being to arrange the mechanism for the purpose in such a manner that a single chain drive from the thresher, in place of the usual pitman drive will serve in connection with suitable means on the header; to operate all the parts on the header, these being the main and spout drapers, the cutter bar, and the reel, to provide for the efficient working of this chain drive irrespective of the transverse angles of setting of the header relative to the thresher; and last but by no means least, to enable the usual gear box, by means of the gears in which the drive is changed from one direction to another, as is necessary, to be mounted on the thresher instead of on the header.

This feature is one of importance. These gear boxes are theoretically oil-tight, but in practice are not. The result is that if the gear box is mounted on the header, and oil is placed therein to have a normal level lower than the box split-line or the shaft bearings, when the header is set at an angle and operating on a side hill, the relative level of the oil is changed, and it escapes from the box. In a very short time, the box is practically empty, and the gears run dry with the consequent rapid wear and deterioration of the gears and shaft bearings.

By mounting the gear box on the thresher, this trouble is avoided, since the thresher is always maintained in a horizontal plane, regardless of the setting of the header.

The above objects I accomplish by means of such structure and relative arrangement of parts as will fully appear by a perusal of the following specification and claims.

In the drawings similar characters of reference indicate corresponding parts in the several views:

Fig. 1 is a fragmentary view of the thresher and header, looking endwise of the former, showing my improved drive mechanism.

Fig. 2 is a view of that portion of the drive means which is mounted on the thresher, looking at the side of the latter.

Referring now more particularly to the characters of reference on the drawings, the numeral 1 denotes in general the longitudinal or side framework of the thresher of the harvester, 2 the header frame, and 3 the header feed-spout pivoted on the header frame, the upper end of the spout being supported on the rail 4 of the feed house 5 of the thresher. 6 represents the usual main drive shaft of the thresher mechanism, extending transversely through the thresher to the side from which the header projects.

My header drive mechanism comprises a chain drive 7 from the shaft 6 to the shaft 8 parallel thereto, said shaft 8 being journaled in the gear box 9 mounted on the frame 1. Operatively connected inside the gear box to the shaft 8 is a shaft 10 at right angles to shaft 8, or extending longitudinally of the thresher and of course also parallel to the pivotal axis of the feed spout. Mounted on the framework 1 above the shaft 8 and parallel to shaft 10 is a countershaft 11, driven by a direct chain drive 12 from shaft 10. Pivoted at one end on the end of shaft 11 and at the other end on the header frame in axial alinement with the pivotal connection of the feed spout therewith is a connection bar 13, which directly links the header to the thresher, and enables the former to have vertical swinging movement relative to the thresher.

Mounted on the shaft 11 is a sprocket wheel 14 and a similar wheel 15 on a shaft 15^a on the header frame concentric with the pivotal connection of the bar 13 with the header frame; a chain 16 passing over these sprockets.

Operatively connected to the shaft 15^a to be driven in connection with the sprocket 15 is a chain drive 17 to operate the cutter-bar of the header, another similar drive 18 to run the various drapers, and still another chain drive 19 to operate the header reel.

It will therefore be seen that I have accomplished in a simple manner the various objects of the invention. The gear box is located on the thresher, where its level is constant; the common drive 16 to the various header mechanisms and its arrangement relative to the connecting bar does away with the universally jointed structure heretofore used for driving; and the header 10 may be raised and lowered, or set at any angle relative to the thresher, without disturbing in the least the operation or efficiency of the drive.

While this specification sets forth in detail the present and preferred construction of the device, still in practice such deviations from such detail may be resorted to as do not form a departure from the spirit of the invention, as defined by the appended 20 claims.

Having thus described my invention what I claim as new and useful and desire to secure by Letters Patent is:

1. In a harvester having a thresher and 25 a header projecting from one side thereof, a connecting bar pivoted on the thresher and on the header, a chain drive between the thresher and header having sprocket wheels concentric with the pivotal 30 connections of the bar, and driving means for the header parts driven in common from the sprocket wheel on the header.

2. In a harvester having a thresher and 35 a header projecting from one side thereof, a connecting bar pivoted on the thresher and on the header, a shaft on the header in axial alignment with the pivotal connection of the bar therewith, drive means for the header parts driven from said shaft, a 40 sprocket wheel on the shaft, another sprocket wheel on the thresher concentric with the pivotal connection of the bar there-

with, and a chain passing about said sprockets.

3. In a harvester having a thresher 45 and a header projecting from one side thereof, a drive shaft on the thresher, a second shaft parallel thereto and driven thereby, a third shaft at right angles to the second shaft and operatively connected 50 thereto, a common member in which said second and third shafts are journaled and in which the connecting means are enclosed, said member being mounted on the thresher, a fourth shaft parallel to and driven by the 55 third shaft, and a drive from said fourth shaft to the harvester.

4. In a harvester having a thresher and a header projecting from one side thereof, a shaft driven from the thresher, a second shaft at right angles thereto and driven thereby, both said shafts being mounted on the thresher, and drive means to the header driven from the second shaft.

5. In a harvester having a thresher and 65 a header projecting from one side thereof, a pair of shafts journaled on the thresher, means operatively connecting the shafts in driving relation, means for driving one of said shafts, and driven means running from 70 the other shaft to the header to operate the parts thereof.

6. In a harvester having a thresher and 75 a header projecting from one side thereof, parallel shafts mounted on the thresher and header respectively, a connecting bar mounted on and extending between the shafts, the latter being connected in driving relation, drive means for the header parts driven from the header-mounted shaft, and drive 80 means for the thresher-mounted shaft.

In testimony whereof I affix my signature.

GEORGE H. HARRIS.
